UNITED STATES PATENT OFFICE

163,074

EMBROIDERED TRIMMING OR SIMILAR ARTICLE

Herman Stern, New York, N. Y., assignor to Beer-Stern Company, Inc., New York, N. Y., a corporation of New York

Application October 26, 1950, Serial No. 12,747

Term of patent 3½ years

(Cl. D3—32)

To all whom it may concern:

Be it known that I, Herman Stern, a citizen of the United States of America, residing in the Borough of Manhattan, city of New York, county of New York, and State of New York, have invented a new, original, and ornamental Design for an Embroidered Trimming or Similar Article, of which the following is a specification, reference being had to the accompanying drawing, forming part hereof.

The figure is a plan view of an embroidered trimming, showing my new design. A design unit is shown between the spaced dot-dash lines and is repeated as shown.

I claim:

The ornamental design for an embroidered trimming or similar article, as shown and described.

HERMAN STERN.
